BAG AND METHOD OF MAKING SAME

John Mitchell Munson, Lakewood, Ohio, assignor
to The Munson Bag Company, Cleveland, Ohio,
a corporation of Ohio

Application September 6, 1932, Serial No. 631,845

7 Claims. (Cl. 93—35)

This invention relates to bags and a method of making same, and is concerned primarily with bags having a finger tab at the upper or open end thereof.

5 Heretofore, as far as I am aware, it has been the accepted practice to form a tab portion by cutting a segment out of the top of the front panel of the bag, leaving the top portion of the back panel free to be gripped by the fingers when 10 opening the bag. This practice, among other things, entailed a waste of stock, reduced the capacity of the bag, and in certain instances entailed a separate cutting operation. While the objection as to waste may not appear of much consequence when the bag material is comprised solely or chiefly of paper, it becomes quite an item when the material cut away is, for example, "cellophane."

I have devised a method of producing a tab 20 type of bag which not only overcomes the foregoing objections but results in a tab which is superior to the conventional type, since it projects above the top of the bag and can be easily grasped by the fingers and does not have a tendency to 25 cause tearing of the bag when opening the latter by the usual snapping action of the forearm. In my method, the tab is cut out from one end of a bag blank and the cut-out portion which defines the tab is utilized in making the bottom fold 30 of the bag made up from the succeeding blank and facilitates formation of such fold. Briefly, the method results in a superior bag with a reduction in cost of manufacture.

I have also devised a step in the tube forming 35 operation which reduces to a minimum the tendency of a machine to clog or jam and also facilitates cutting of the tube into suitable bag lengths or blanks.

To obtain a more complete understanding of 40 the method and the advantages to be obtained by its adoption, reference is had to the accompanying drawings, wherein:—

Figs. 1 and 2 are diagrammatic views in side elevation and plan of such parts of a tube forming and cutting machine as will facilitate an understanding of this phase of my method;

Fig. 3 is a top plan view of a tube just prior to complete detachment of the severed form by the pick up rolls;

45 Figs. 4 and 5, respectively, are bottom and top plan views of a form or blank after passing through the tube forming and cutting mechanism and ready for the initial bottom folding operation;

Figs. 6, 7 and 8 illustrate the successive steps of 50 the bottom folding operation.

First referring to Figs. 1 and 2, 5 designates diagrammatically a roll of stock, 6 a glue pot and 7 a glue wheel for the longitudinal seam of the bag, 8 a former guide roll, 9 the tube former or mandrel, 10 draw rolls, 11 the former tail and 12 and 13 the top and bottom knives which coact therewith, and 14 the pick-up rolls for discharging the completed blank ready for the bottom folding operation.

Up to the former tail, the parts may be of 10 conventional design, the stock S being taken from the roll 5, the glue applied to the longitudinal seam 15 by the wheel 7, then passing over the guide roll 8 and the former 9, the sides of the tube being lapped over and glued as the 15 latter passes through the draw rolls 10.

The top surface of the former tail is provided with slots 15 and 16 and the bottom surface with a slot 17, the latter being given the contour of the tab of the bag, and the knives 12 20 and 13 are shaped to coact with these slots, as will be understood. It will be seen from the contour of the slots 15 and 16 that longitudinal slits 12^a note Figs. 3, 4 and 5, will be formed in the top panel of the bag, leaving a flap 18, and 25 that the tube will be severed (not completely in the present method) transversely in the slots 15 and arctately and transversely in the slots 17, the arcuate cut defining a tab 19 at the top of the bag and a cut-out segment 20 at the 30 bottom thereof.

The knives 12 and 13 are dimensioned so as to 35 cut through all but a fraction of the tube, as indicated at 21, Fig. 3, and the peripheral speed of the pick-up rolls 14 is gauged so as to be slightly in excess of that of the draw rolls 10. The result is that each blank is gripped by the rolls 14 and the tube is constantly maintained at a slight tension while being acted on by the knives 12 and 13. The uncut portion on each 40 side of the tube need be but slight, or just sufficient to maintain a certain amount of pull on the tube. When this pull or tension becomes greater than the tensile strength of the uncut portions 21, the blanks are separated and kicked 45 out or discharged by the rolls 14.

Practical experience has shown that this method results in a clean cutting action by the knives 12, 13 and eliminates irksome jamming or clogging and distortion of the blanks frequently 50 encountered in machines where the blanks are completely severed by the knives, leaving the outgoing end of the tube loose and wherein the cut blanks are in a sense pushed into the pick-up rolls instead of being pulled by said rolls. 55

The blank shown in Figs. 4 and 5 has been formed and cut and is ready for the folding mechanism. Since such mechanism may be of any suitable type, it is not shown. The blank 5 is preferably given a diamond fold as shown in Figs. 6, 7 and 8, although it will be understood that certain variations in fold may be adopted for the purpose of advantageously utilizing the flap 18 and/or cut out portion 20. However, since 10 this type of fold is well understood in the art, it serves as convenient means of illustrating the method.

In making the fold, the bottom side wall which carries the flap 18 is folded back on the line 22 and at the same time the sides are collapsed inwardly and creased on the lines 23, suitable glue or adhesive substance being applied, as for example, at 24.

The next step is shown in Fig. 7, the flap 18 being folded on the line 25 and ironed down and glued in place. The final step is shown in Fig. 8, the bottom portion of the opposite side wall being folded on the line 26, ironed down and glued in place.

25 It will be seen that the tab 19 is not only superior to the cut-out type of tab but causes no waste of material since the cut-out portion which defines the tab is used in the bottom fold where, if anything, it is an asset since it facilitates the folding back of the flap 18. Furthermore, the flap 18, being of single-wall thickness, makes a neater fold and can be more easily glued than the bulky double wall which would otherwise be present and which has a tendency to spring back

35 when ironed down on fresh glue.
It will be understood that advantages other than
those enumerated may be derived from my meth-
od and that certain variations in procedure and
sequence of steps may be practiced without de-
parting from the scope of the invention as de-
fined by the appended claims.

I claim:—

1. In the manufacture of bags, the method which consists in forming a continuous tube from stock material, severing the tube into a series of blanks in such manner as to define a projecting tab at one end of the blank and a cut-out portion defining the tab at the opposite end of the blank, and then forming a bottom fold at the end of the blank having the cut-out portion.

2. In the manufacture of bags, the method which consists in forming a continuous tube from stock material, severing the tube transversely into

a series of blanks, the one side wall of the tube at the point of severance being formed with a projection defining a tab, and utilizing the end of each blank which is formed with a projection as the open end of a bag and the meeting end of the adjacent blank from which the projection is cut as the bottom of a bag.

3. In the manufacture of bags, the method which consists in forming a continuous tube from stock material, severing the tube into a series of blanks having a projection at one end thereof defining a tab and a slit portion at the opposite end defining a folding flap, and forming a bottom fold at the ends of the blanks having said flap. 10 15

4. In the manufacture of bags, the method which consists in severing a series of blanks from a continuous tube, the cut on one side of the tube defining a tab and the cut on the other side of the tube defining a folding flap, then forming a bottom fold at the end of the blank formed with a flap, and utilizing the meeting end of the adjacent blank as the top of another bag. 20

5. In the manufacture of bags, the method which consists in severing a continuous tube into a series of blanks, one side of the tube being cut transversely and arcuately to define a tab, and the opposite side of the tube being cut transversely and also slit substantially longitudinally to define a folding flap, forming a bottom fold at the slit end of the blank and utilizing the adjacent end of the succeeding blank as the top of another bag. 25 30

6. In the manufacture of bags, the method which consists in forming a continuous tube from stock material, severing the tube into a series of blanks, one wall of the tube being cut transversely and also out of alignment to the transverse to define a tab and the other wall of the tube being cut transversely and also slit at substantially right angles to the transverse to define a folding flap, and forming a bottom fold at the slit end of the blank and utilizing the meeting end of the adjacent blank as the open end of another bag. 45

7. The method of manufacturing bags having finger tabs at the open end thereof, which consists in fashioning a series of blanks with one side wall of a blank projecting beyond the opposite side wall thereof to define a tab, slitting the opposite end of the blank to define a folding flap, and forming a bottom fold with said flap. 50
